UNITED STATES PATENT OFFICE.

WILLIAM JOSIAH STEWART, OF LYNNVILLE, TENNESSEE.

GARDEN-PLOW.

SPECIFICATION forming part of Letters Patent No. 692,941, dated February 11, 1902.

Application filed August 26, 1901. Serial No. 73,367. (No model.)

To all whom it may concern:

Be it known that I, WILLIAM JOSIAH STEWART, a citizen of the United States, residing at Lynnville, in the county of Giles and State 5 of Tennessee, have invented a new and useful Garden-Plow, of which the following is a specification.

This invention relates to garden-plows.

One object of the invention is to present a 10 plow having handles of such construction as to remove all strain and abrasive action from the hands of the operator and in which direct front thrust may be applied to the handles, thereby to cause effective operation of the 15 plow.

A further object is to provide a plow having a rear or furrow wheel of such construction as automatically to adjust itself to the furrow, whether the same be straight or 20 crooked, thereby insuring proper operation of the shovel.

A further object is to provide a novel form 25 of shovel-beam and furrow-wheel bracket by which the parts of the frame will be thoroughly braced and racking or lost motion between the parts thereof will be obviated.

A final object is to present a simply-constructed, highly-durable, and thoroughly-efficient form of garden-plow which may be operated 30 to produce the best results with a minimum output of energy.

With these and other objects in view, as will appear as the nature of the invention is better understood, the same consists in the 35 novel construction and combination of parts of a garden-plow, as will be hereinafter fully described and claimed.

In the accompanying drawings, forming a part of this specification, and in which like 40 numerals of reference indicate corresponding parts, there is illustrated a form of embodiment of the invention capable of carrying the same into practical operation, it being understood that the elements herein exhibited 45 may be varied or changed as to shape, proportion, and exact manner of assemblage without departing from the scope of the invention, and in the drawings—

Figure 1 is a view in perspective of a garden-plow constructed in accordance with this 50 invention. Fig. 2 is a view in top plan, the

front ends of the handle-bars being broken away.

Referring to the drawings, 1 designates the front or supporting wheel, and 2 the rear or 55 furrow wheel, the latter being of less diameter than the former, as is usual in implements of this character. The front wheel supports the shovel-beam 3, comprising two members, each of which is composed of a straight body 60 portion 4 and a downwardly and forwardly curved portion 5, constituting the shovel-standard, the portion 5 being bent to form a loop 6, constituting the lower terminal of the standard. While the shovel-beam is herein 65 shown as being made of a single piece of metal and is by preference so constructed on account of simplicity and strength, it is to be understood that the same may be composed of two pieces of metal suitably associated. 70 The members of the shovel-standard are spaced apart a sufficient distance to permit insertion therebetween of the bolts 7, that hold the shovel 8 associated with the standard, the rear ends of the bolts carrying nuts which 75 bear against the rear side of the standard, and thereby hold the shovel rigidly associated therewith.

The shovel may be of any preferred construction, and therefore needs no specific description. The forward ends of the shovel-beam members are transversely orificed for the reception of the axle 9 of the supporting-wheel 1, the ends of the shovel-beam bearing against the hub 10 of the wheel, as clearly 85 shown in Fig. 2, and engaging the outer ends of the axle 9 are the lower ends of the handle-bars 11, nuts 12, screwed on the ends of the axle, serving to hold the handle-bars and 90 shovel-beam members associated therewith.

The handle-bars, which constitute one of the essential features of the invention, are provided with handles 13 of peculiar construction, and designed, as before pointed out, to relieve strain from the hand of the operator 95 and to enable him to apply direct end thrust thereto. Each handle 13 comprises an offset, which may be either integral with the bar or secured thereto and is provided with a curved slot 14, through which the fingers of the operator are passed, and with a forward hand-grip 15, the outer wall of which is shaped to 100

conform to the palm of the hand when the same is closed. In other words, the hand-grip is shaped somewhat like a saw-handle, this being a structure that readily fits the hand of the user and enables him firmly to grip the same. As shown in Fig. 1, the handles are disposed below the plane of the top of the handle-bars, and the outer wall of the hand-grip is disposed at an angle to the handle-bar that will be most conducive to ease in use and for imparting a direct forward thrust to the plow. In this connection it is to be noted that the peculiar form of handle herein shown is equally well adaptable to any form of agricultural implement where its use will be found advantageous, so that its employment is not to be confined to garden-plows alone. To render the handle-bars rigid against side shake and also to hold them at the proper distance apart, the same are connected near their outer ends by a rung 16, and, if found necessary, two or more rungs may be employed, as will be obvious.

The furrow-wheel 2 is supported in operative position by a pair of wheel-brackets 17, each comprising a straight upper end portion 18, a rearward-curved lower end portion 19, and an angularly-disposed center portion 20. The lower curved end portions or arms 19 of the bracket are provided each with a horizontally-disposed slot 21, in which works the ends of the axle 22 of the furrow-wheel, the provision of the slots permitting the furrow-wheel to have a limited lateral swinging movement, thereby to cause the same automatically to adjust itself to follow the furrow whether the same be straight or crooked, and thus cause the shovel always to follow the furrow or line. Near the angular offsets 20 the bracket is secured to the rear portion of the shovel-beam by a bolt 23, and by this arrangement the said beam is supported at the proper distance above the ground and is rigidly braced against lateral shake. The upper end portions 18 of the bracket members are each provided with a plurality of openings 24, through each of which passes a bolt 25, that projects through a handle-bar, a nut 26 carried by the bolt serving to clamp the end of the bracket rigidly to the handle-bar. By the provision of the plurality of openings 24 in the bracket members the handle-bars may be raised or lowered to suit the height of the operator, and in addition the bolts that hold the bracket members associated with the handle-bars also serve the further function of supporting the handle-bars and holding them rigidly in posi-

tion against lateral play. An object had in view in this invention is to construct the same of the fewest possible number of parts 60 and to associate the parts in such manner as positively to overcome any tendency of having the same disassociated from racking and strains incident to use, and this object, as will be apparent, has been accomplished in 65 a thoroughly practical manner by the disposition of the parts as shown.

When the implement is in use, the shovel will be kept in the furrow by reason of the self-adjusting furrow-wheel 2, as before pointed out, and, further, the implement may be operated close up to and around plants or other obstructions by being tilted to the right or left, as the case may be, and will under these conditions, owing to the manner of 75 mounting the furrow-wheel, be thoroughly effective in operation. By reason of the peculiar construction of the handles the hands of the operator will never become blistered or strained, and by their employment the labor of operating the plow will be reduced to a minimum.

Having thus fully described the invention, what I claim as new, and desire to secure by Letters Patent, is—

1. In a garden-plow, the combination with the handle-bars, of brackets secured thereto and provided at their lower ends with horizontally-disposed slots, and a furrow-wheel having the ends of its axle working in the 90 slots.

2. In a garden-plow, the combination with the handle-bars, of brackets adjustably connected therewith and provided at their lower ends with horizontally-disposed slots, and a furrow-wheel having the ends of its axles working in the 95 slots.

3. In a garden-plow, the combination with handle-bars carrying at their front end a supporting-wheel, of brackets secured to the 100 handle-bars and provided at their lower ends with horizontally-disposed slots, a furrow-wheel having the ends of its axle working in the slots, and a shovel-carrying beam having its forward end mounted on the supporting-wheel axle and its rear end connected with the said brackets.

In testimony that I claim the foregoing as my own I have hereto affixed my signature in the presence of two witnesses.

WILLIAM JOSIAH STEWART.
